UNITED STATES PATENT OFFICE.

FRED STEBLER, OF RIVERSIDE, CALIFORNIA, ASSIGNOR TO STEBLER PARKER CO., OF RIVERSIDE, CALIFORNIA, A CORPORATION OF CALIFORNIA.

BRUSH.

Application filed December 19, 1921. Serial No. 523,315.

To all whom it may concern:

Be it known that I, FRED STEBLER, citizen of the United States, residing at Riverside, in the county of Riverside and State 5 of California, have invented certain new and useful Improvements in Brushes, of which the following is a specification.

Brushes now employed in fruit treating apparatus for the polishing, brushing or 10 drying of the fruit as conveyed from one machine, apparatus or point to another, and more particularly set forth in Letters Patent No. 1,222,645, dated April 17th, 1917, are costly to manufacture and to repair 15 when the bristles thereof become worn, and with the view of increasing the life and efficiency of said brushes and reducing the cost of manufacture thereof and replacement, the hereinafter described brush has 20 been designed.

This invention consists primarily in providing a brush core either polygonal or cylindrical in cross section with a plurality of independent spiral channels or grooves disposed spirally in the peripheral surface thereof from end to end in parallel relation for the reception of independent members mounting bristles or other suitable brush forming elements; and further in grouping 25 bristle holding members mounting bristles of the same length with bristle holding members mounting bristles of a greater or less length in such a manner in the grooves as to provide a spiral rib or channel in the 30 peripheral surface of the brush from one end to the other.

Among the objects of the invention are to provide a construction wherein any given row of bristles is adapted for ready 40 replacement and removal, one wherein the bristle holding member to be associated with any particular groove may be positioned therein independently of the others, or a series of said members may be positioned 45 within their respective grooves providing a group of bristles adapted for trimming to provide a brush of any desired exterior cross section on a cylindrical or polygonal core; to provide a core construction of the 50 built up type, which is capable of being cheaply manufactured, and which is adapted for receiving mounting shafts of the well known type.

With the above mentioned and other objects in view, the invention consists in the

novel construction and combination of parts hereinafter described, illustrated in the accompanying drawings, and set forth in the claims hereto appended, it being understood that various changes in the form, proportion, size and minor details of construction within the scope of the claims may be resorted to without departing from the spirit or sacrificing any of the advantages of the invention.

To more fully comprehend the invention reference is directed to the accompanying drawings, wherein:—

Figure 1 is a view in end elevation of the preferred embodiment of my invention disclosing the built up core.

Figure 2 is a view in plan of a portion of one of my improved brush mounting cores disclosing the independent spiral grooves, and

Figure 3 is a view similar to Figure 2 illustrating bristles held within said grooves.

Referring to the drawings wherein like characters of reference designate corresponding parts, 1 indicates a shaft extending through a central opening 2 in a rectangular core box 3, the length of the desired brush. To the faces of said core box 3 are secured the brush back forming members 4 grouped about said core box to provide a polygonal core 5, said members 4 in cross section resembling rhomboidal sectors, and said sectors are secured together throughout their length by the retaining dowels 6' extending angularly from adjacent faces of co-operating sectors into adjacent sectors, as in Figure 1 of the drawings.

The peripheral surface of the core is formed from end to end with the independent continuous separate spiral grooves 6 each opening at its opposite end preferably at the ends of said core. Within each of said grooves is adapted to be positioned a bristle mounting and retaining member 7, preferably of flexible twisted wires and mounting throughout its length suitable brush bristles preferably arranged in tufts 8, the tufts being held to the wire in any suitable manner as by twisting several strands of the wire together and about the base of the tufts.

In the drawings, I have illustrated an embodiment of the invention wherein a spiral groove 9 is formed by the bristles longitudinally of the brush, and this construction is accomplished preferably in the following

manner:—In certain grooves 6, preferably those adjacent each other and of a number to give the desired width to the spiral groove 9 in the brush, are positioned the respective 5 bristle mounting members 7 carrying the tufts 8 of the shortest length to form the base 10 of the spiral groove in the brush, and to insure the uniform length of said bristles, the same are preferably trimmed as 10 desired. The intervening grooves 6 than receive their bristle holding members 7 mounting the bristles of the greater length to form the rib 11 of the spiral in the brush, and these bristles are in turn trimmed to a uniform 15 length and in this manner the brush is provided having a spiral groove 9 in the brush surface.

In the present embodiment, I have illustrated a core polygonal in cross section, and 20 when building a brush on this type of core, I preferably position the core within a lathe, and while rotating cut the independent grooves 6 spirally therein. In this type of brush, it is only necessary to trim the ends of 25 the bristles to present faces parallel with the core faces in order to provide a polygonal brush if the same is desired; however, the brush may be cylindrical in cross section and if desirable the core may also be cylindrical 30 in cross section and the ends of the bristles thereof may be trimmed to provide a brush polygonal in cross section.

While I have illustrated the invention in 35 the form of a polygonal brush, it is to be understood that I am not to be limited to such as the essence of the present invention is in the providing of separate grooves or channels spirally of a rotatable core, and each for receiving bristles or brush material 40 carried by independent retaining means enabling the ready removal or replacement of the material in any one groove for the full length of the core without disturbing the material in any other groove.

45 The carrying of the brush forming material in mounting members such as twisted wire enables a user when a brush becomes worn to readily replace the bristles thereof, or of any row thereof, without returning the 50 brush to the factory, and in some cases without removing the brush from the machine in which it is mounted. This mounting for the bristles enables a brush factory to carry the same in lengths for ready shipment.

55 While throughout the specification and claims I have referred to bristles, it is to be understood that any suitable type of brush forming material may be employed, such as wire if desired.

60 While I have described in the present application the method of making the brush, this application is directed to the brush per se, and the method of making the brush is reserved for the subject matter of another application.

Having thus described my invention, what I claim as new, and desire to protect by Letters Patent of the United States is:—

1. A brush comprising a core provided on its surface with a plurality of annular spiral 70 grooves each independent and separate from the other and extending from one end of the core to the other, a plurality of flexible tuft mounting members, one positioned within and extending from one end to the other of 75 each groove, means for anchoring the ends of each tuft mounting member to the core, and a plurality of brush tufts carried by each mounting member and projecting radially of the core surface. 80

2. A brush comprising a core provided on its surface with a plurality of annular spiral grooves each independent and separate from the other and extending from one end of the core to the other, a plurality of flexible tuft 85 mounting members, one positioned within and extending from one end to the other of each groove, means for anchoring the ends of each tuft mounting member to the core, and a plurality of brush tufts carried by each 90 mounting member and projecting longitudinally of the core surface, the brush tufts of certain tuft mounting members being of a length greater than the tufts of the other tuft mounting members providing a spiral 95 groove disposed longitudinally of the brush and formed by the difference in length of said tufts.

3. A brush comprising a core provided on its surface with a plurality of uniformly spaced independent spiral grooves extending from one end to the other thereof, a bristle 100 mounting member co-operating with each groove for its full length, bristles carried throughout the length of each member and held thereby radially of the core affording a bristle surface surrounding the core, the bristles of certain members being of a length greater than those of other members affording a spiral rib extending longitudinally 105 throughout the length of the brush. 110

4. A brush comprising a core provided on its surface with a plurality of uniformly spaced independent spiral grooves each extending continuously from one end to the other thereof, a bristle mounting member co-operating with each groove for its full length, bristles carried by each member throughout its full length and held thereby 115 radially of the core affording a bristle surface surrounding the core, the bristles carried by certain mounting members being shorter than those of the other mounting members, and said short bristle mounting members being grouped providing a spiral 120 rib extending longitudinally throughout the length of the brush. 125

5. A brush comprising a core provided on its surface with a plurality of uniformly spaced independent spiral grooves, each extending 130

continuously from one end to the other thereof, a bristle mounting member co-operating with each groove for its full length, bristles carried by each member throughout its full 5 length and held thereby radially of the core affording a bristle surface surrounding the core, each of said mounting members adapted for removal from the core as a unit and independently of each other.

10 6. A brush comprising a core provided on its surface with a plurality of uniformly spaced independent spiral grooves, each extending continuously from one end to the other thereof, a bristle mounting member co-operating 15 with each groove for its full length, bristles carried by each member throughout its full length and held thereby radially of the core affording a bristle surface surrounding the core, the outer ends of the bristles carried by 20 certain bristle mounting members being closer to the periphery of the brush than the ends of the bristles of certain other bristle mounting members affording a spiral rib extending longitudinally throughout the 25 length of the brush.

7. A brush comprising a core provided on its surface with a plurality of uniformly spaced independent spiral grooves each extending continuously from one end to the other thereof, a bristle mounting member co-operating 30 with each groove for its full length, bristles carried by each member throughout its full length and held thereby radially of the core affording a bristle surface surrounding the core, the bristles car-

ried by certain mounting members being shorter than those of the other mounting members and said short bristle mounting members being grouped providing a spiral rib extending longitudinally throughout the 40 length of the brush, the bristle surface of said brush being polygonal in cross section affording a plurality of faces extending longitudinally throughout the length of the brush.

45 8. A brush for the described purpose comprising a hollow core box, a plurality of brush back forming members carried thereby and enclosing the same, said members being substantially rhomboidal in cross section 50 with corresponding side edges in contact, their peripheries forming a substantially cylindrical bristle mounting roller, means for uniting said members about said core, said members on their periphery mounting radially disposed brush forming bristles.

9. A brush for the described purpose comprising a tubular built up core box, substantially rectangular in cross section, a plurality 60 of brush back forming members carried thereby and enclosing the same, means for uniting said members about said core with their peripheries forming a substantially cylindrical bristle mounting roller, said roller on its periphery mounting a plurality of 65 brush forming bristles.

In testimony whereof I have signed my name to this specification.

FRED STEBLER.
